Filed Mar. 18, 1966, Ser. No. 1,535

Term of patent 14 years

(Cl. D62—4)

FIG. 1

FIG. 2

FIG. 3

FIG. 4

FIGURE 1 is a perspective view of an air conditioner embodying my new design, showing a vent door thereon in a partially-open position;

FIG. 2 is a similar view but showing the vent door in its closed position;

FIG. 3 is like FIGS. 1 and 2 but showing the vent door in its fully-open position;

FIG. 4 is a top plan view of the air conditioner as seen from above FIG. 2; and

FIG. 5 is a side view thereof taken from the left of FIG. 2.

The side not shown is like the side illustrated, and the bottom and back of the air conditioner are plain and unornamented.

I claim:
The ornamental design for an air conditioner, substantially as shown and described.
